US00D547899S

(12) **United States Design Patent** (10) **Patent No.:** **US D547,899 S**
VanderSchuit (45) **Date of Patent:** **** Jul. 31, 2007**

(54) **ELECTRIC LIGHT**

(76) Inventor: **Carl R. VanderSchuit**, 751 Turquoise St., San Diego, CA (US) 92109

(**) Term: **14 Years**

(21) Appl. No.: **29/243,639**

(22) Filed: **Nov. 29, 2005**

Related U.S. Application Data

(63) Continuation-in-part of application No. 10/998,347, filed on Nov. 24, 2004, now Pat. No. 7,063,432, which is a continuation-in-part of application No. 10/189,822, filed on Jul. 3, 2002, now Pat. No. 6,824,289, which is a continuation-in-part of application No. 09/627,961, filed on Jul. 28, 2000, now Pat. No. 6,416,198.

(57) **CLAIM**

The ornamental design for the electric light, as shown and described.

DESCRIPTION

FIG. 1 is an upper perspective view of the electric light, showing my new design;

FIG. 2 is a lower perspective view of the electric light shown in FIG. 1;

FIG. 3 is a top plan view of the electric light shown in FIG. 1;

FIG. 4 is a bottom plan view of the electric light shown in FIG. 1;

FIG. 5 is a front elevation view of the electric light shown in FIG. 1;

FIG. 6 is a rear elevation view of the electric light shown in FIG. 1;

FIG. 7 is a left elevation view of the electric light shown in FIG. 1; and,

FIG. 8 is a right elevation view of the electric light shown in FIG. 1.
